Primary Examiner—Martie K. Holtje
Attorney, Agent, or Firm—Trapani & Molldrem**[57] CLAIM**

The ornamental design for an organizer contact record leaf, as shown and described.

DESCRIPTION

FIG. 1 is a front elevational view of an organizer contact record leaf showing our new design; and, FIG. 2 is a rear elevational view thereof.

The organizer contact record leaf is flat and of conventional thickness.

The stippled shading in the drawing indicates color contrast.
